UNITED STATES PATENT OFFICE

2,511,932

LIQUID FUEL STOVE WITH SIMULTANEOUS
FUEL AND AIR CONTROLLewis G. McKenzie and Arthur R. Kingsley,
Houghton Lake, Mich.

Application May 9, 1947, Serial No. 747,082

2 Claims. (Cl. 126—93)

1

This invention relates to new and useful improvements in liquid fuel stoves and the primary object of the present invention is to provide a stove including novel and improved means for simultaneously controlling the air supply with a proper amount of fuel supplied to the stove.

Another important object of the present invention is to provide a stove wherein are fitted a series of baffles so designed as to direct the heated air in the stove towards an exhaust pipe in a retarded manner thereby retaining heat for long periods of time within the stove.

A further object of the present invention is to provide an inexpensive stove comprising novel and improved draft regulating means so designed to permit the use of the stove with various heights of chimneys.

A still further purpose of the present invention is to provide a stove that is simple and practical in construction, efficient and reliable in use, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view of the present invention, with parts of the exhaust pipe broken away;

Figure 2 is a side elevational view of Figure 1;
Figure 3 is a bottom plan view of Figure 1;

Figure 4 is a vertical sectional view taken on line 4—4 of Figure 2;

Figure 5 is a horizontal sectional view taken on line 5—5 of Figure 4; and,

Figure 6 is a horizontal sectional view taken on line 6—6 of Figure 4.

Referring now to the drawings in detail, wherein for the purpose of illustration, there is disclosed a preferred embodiment of the present invention, the numeral 10 represents generally a cylindrical stove including an air chamber 12, a top 14, a bottom 16 and legs 18 carried by the bottom for supporting the stove in an elevated position.

Suitably mounted on the bottom 16 and centrally located therein is an axial tubing 20 closed at its upper end by cap 22, on which is secured an upper baffle plate 24.

Embracing the lower portion of tubing 20, is a lower baffle plate 26 the outer edge of which is spaced from the inner wall of the stove.

2

Spaced between the baffle plate 24 and 26, is an intermediate baffle plate 28, the outer edge of which is suitably secured to the inner wall of the stove. This plate 28 is provided with an annular opening 30 that surrounds the tubing 20.

An upper series of circumferentially spaced slits 32 are provided in tubing 20 between baffle plates 24 and 28. Intermediate circumferentially spaced slits 34 are provided in the tubing between plates 28 and 26, and a lower series of slits 36 are also provided in the tubing between plates 26 and the bottom 16. These slits furnish the necessary outlet means for the air heated in the tubing.

15 Mounted on the stove, near the bottom 16, is a carburetor 38 which is connected to a fuel line 40 in a usual manner. A lead pipe 42 carried by the carburetor extends through an air and liquid seal 44 in bottom 16 and communicates

20 with a liquid absorbent wick 46 embracing the lower end of tubing 20.

25 Mounted on the carburetor is a bearing sleeve 48 in which is journaled a shaft 50. A carburetor valve control rod 52 is journaled in a bracket 54 carried by the stove and a pinion 56 carried by said rod engages the upper pinion 58 carried by shaft 50. The lower pinion 60 carried by shaft 50 engages a gear 62 journally mounted to the bottom 16.

30 A series of openings 64 of various diameters, are provided in gear 62 for selective positioning under the lower open end of tubing 20.

35 In practical use of the stove, by turning the finger gripping knob 66 carried by rod 52, the carburetor valve and gear 62 are simultaneously regulated to control both the air and the fuel entering the stove.

40 When the wick is lighted by a flame from a match or the like, the heated air will pass around the lower baffle, through the opening in the intermediate baffle, around the upper baffle, and hence through the exhaust pipe 68 carried by the stove. The baffles retard the direct flow of the heated air in the stove thereby retaining the heat in the stove for long periods of time.

45 For additional draft control means for the stove, there is provided a plate 70 pivotally mounted on the cover 14 for regulated adjustment over opening 72 in the cover.

50 In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. In a stove having a bottom wall and an axial tubing therein, a liquid fuel line for supplying fuel to said stove, said bottom wall having an air vent communicating with said tubing, an annular plate pivoted at its center adjacent the center of said bottom wall, said plate including a plurality of circumferentially spaced apertures of various diameters for selectively registering with the air vent, said fuel line including a carburetor and valve means for controlling the flow of fuel through the carburetor, a control rod for said carburetor, and gearing connecting said control rod to said plate for simultaneous proportional regulation of the air and fuel supply to the tubing.

2. In a stove having a bottom wall and an axial tubing therein, a liquid fuel line for supplying fuel to said stove, said bottom wall having an air vent communicating with said tubing, an annular plate pivoted at its center adjacent the center of said bottom wall, said plate including a plurality of circumferentially spaced apertures of various diameters for selectively registering with the air vent, said fuel line including a carburetor and

10
15

valve means for controlling the carburetor, a control rod for said carburetor, and gearing connecting said control rod to said plate for simultaneous proportional regulation of the air and fuel supply to the tubing, said gearing including a bearing rigidly attached to said carburetor, a driven shaft rotatably supported in said bearing, gears connecting said control rod to said driven shaft, said plate having an externally toothed annular edge and a gear fixed on said driven shaft engaging the toothed edge of said plate.

LEWIS G. MCKENZIE.
ARTHUR R. KINGSLEY.
